Filed Sept. 17, 1962, Ser. No. 71,725

Term of patent 14 years

(Cl. D83—1)

FIG. 1.

FIG. 5.

FIG. 2.

FIG. 4.

FIG. 6.

FIG. 3.

FIGURE 1 is a top plan view of a regulator for an underwater breathing apparatus or the like, showing my new design, the parallel lines disclosed on the surface of the knob element represent surface ornamentation as indicated by FIG. 6.

FIG. 2 is a side elevational view thereof;

FIG. 3 is an end view thereof;

FIG. 4 is a bottom plan view of the regulator;

FIG. 5 is a partial transverse sectional view thereof, taken along line 5—5 of FIG. 1, at an enlarged scale; and

FIG. 6 is a longitudinal sectional view thereof, taken along line 6—6 of FIG. 4, at an enlarged scale.

The dominant features of the design reside in the portions shown in full lines.

I claim:

The ornamental design for a regulator for underwater breathing apparatus or the like, substantially as shown and described.
